Primary Examiner — Jack Reickel*Assistant Examiner* — Sydney M Evans(74) Attorney, Agent, or Firm — Banner & Witcoff, Ltd.(57) CLAIM

The ornamental design for a clasp as shown and described.

DESCRIPTION

FIG. 1 is a front perspective view of a clasp showing my new design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken line showing of the small circular regions on the clasp form no part of the claimed design.

1 Claim, 6 Drawing Sheets(56)
